CLAIM

The ornamental design for a travel mug, as shown and described.

DESCRIPTION

FIG. 1 is a perspective view of a first embodiment of a travel mug showing our new design;

FIG. 2 is a front view of the embodiment shown in FIG. 1;
FIG. 3 is a rear view of the embodiment shown in FIG. 1;
FIG. 4 is side view of the embodiment shown in FIG. 1;
FIG. 5 is another side view of the embodiment shown in FIG. 1;

FIG. 6 is a top view of the embodiment shown in FIG. 1;
FIG. 7 is a bottom view of the embodiment shown in FIG. 1;

FIG. 8 is a rear perspective view of the embodiment shown in FIG. 1;

FIG. 9 is a perspective view of a second embodiment of a travel mug;

FIG. 10 is a front view of the embodiment shown in FIG. 9;
FIG. 11 is a rear view of the embodiment shown in FIG. 9;
FIG. 12 is side view of the embodiment shown in FIG. 9;
FIG. 13 is another side view of the embodiment shown in FIG. 9;

FIG. 14 is a top view of the embodiment shown in FIG. 9;
FIG. 15 is a bottom view of the embodiment shown in FIG. 9; and,

FIG. 16 is a rear perspective view of the embodiment shown in FIG. 9.

The oblique line shading shown in FIGS. 9-16 represents a
brushed metallic surface.
